WINDOW SCREEN AND FRAME

Raymond W. Jessup, San Diego, Calif.

Application August 16, 1949, Serial No. 110,583

4 Claims. (Cl. 160—397)

1

My invention relates to a window screen and frame, more particularly for use adjacent to building window sash, and the objects of my invention are:

First, to provide a window screen and frame of this class in which louver screen may be very tightly interlocked with the frame without distorting any of the louvers thereof;

Second, to provide a window screen and frame of this class in which the exact spacing of the rows of louvers from opposite edges of the frame may be accomplished;

Third, to provide a window screen and frame of this class in which a rectangular in cross-section frame structure is provided with a channel portion at the outer side thereof for interlocking the screen therein, and a rectangular in cross-section structure inwardly of the locking channel, whereby the channel does not bear tension stresses exerted by the screen when locked therein, so that distortion of the channel is substantially eliminated and stresses of the tightened screen are carried by the rectangular in cross-section portion of the frame inwardly of the channel portion thereof;

Fourth, to provide a window screen and frame of this class in which the interlocking channel at the outer edge of the rectangular in cross-section screen frame structure provides for concurrent interlocking of the screen in the channel by screen locking members, and the induction of tension in the screen intermediate channels at opposite edges of the frame;

Fifth, to provide a window screen and frame of this class in which the screen in connection with the frame is maintained in tension intermediate two opposed channels at opposite sides of the frame, while the remaining opposite sides, at ninety degrees to said first-mentioned opposite sides, are secured in overlapped relationship beneath a channel molding which retains the screen in secure engaged relation with the frame at its unsecured edges without distortion of the louvers of the screen;

Sixth, to provide a window louver screen and frame of this class which is very neat and mechanically compact;

Seventh, to provide a window louver screen and frame of this class in which the tension in the screen is effectively maintained under various conditions of service;

Eighth, to provide a window louver screen and frame of this class which is very simple and easy to assemble and install; and

Ninth, to provide a window louver screen and

2

frame of this class which is very simple and economical of construction, efficient, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a fragmentary side elevational view of my window louver screen and frame, showing portions thereof broken away and in section to amplify the illustration; Fig. 2 is an enlarged fragmentary sectional view, taken from the line 2—2 of Fig. 1; and Fig. 3 is a fragmentary sectional view, taken from the line 3—3 of Fig. 1.

Similar characters of reference refer to similar parts and portions throughout the several views of the drawings.

The frame 1, screen 2, screen locking members 3, molding channels 4, 5, 6 and 7, and the screws 8 constitute the principal parts and portions of my window louver screen and frame.

The frame 1 is a rectangular frame, composed of a cross-sectional shape, as shown in Fig. 2 of the drawings, wherein the outer edge of the frame 1 is provided with a channel portion 1a, having an open side 1b, provided with a folded edge portion 1c, which is directed toward the enclosed side of the channel 1a. The cross-sectional structure of this frame 1 also incorporates an integral rectangular in cross-section stress-bearing structure 1d, which is inwardly of the channel 1a, and which supports tension of the screen 2 locked in the channel 1a by means of the screen locking members 3.

The screen locking members 3 are circular in cross-section, or may be angular in cross-section, if desired, and extend along each straight side of the frame 1 in the channel portions 1a, and frictionally lock the edge portions 2a of the louver

screen 2 at two opposed sides of the screen frame 1 parallel to the louver screen slats 2e and transversely of the integral tension strips 2d. Thus, the tension strips 2d are engaged by the screen locking members 3 and are frictionally held, which maintains said strips 2d in tension for holding the screen 2 tight and secure on the frame 1. The screen 2 is a substantially conventional louver screen, having a plurality of rows of louver portions 2b, which are angularly disposed, as shown in Fig. 2 of the drawings. The edges 2c

of the louver screen 2, disposed at right angles to the edges 2a interlocked by the screen locking members 3, are arranged in overlapped relationship with the inwardly extending edge portions 4a and 5a of the molding channels 4 and 5. Thus, tension in the louver screen 2 is transversely of the louvers and longitudinally of the rows of louvers 2b, all as shown best in Fig. 1 of the drawings.

The molding channels 4, 5, 6 and 7 are all substantially similar in cross-section, and therefore the molding channel 4, as shown in Fig. 3, will be described herein for the purpose of disclosing the shape of all of the channels 4, 5, 6 and 7. At the edge portion 4a of the molding channel 4, the overlapped relationship with the edge 2c of the screen 2 is sufficient to retain the screen 2 securely against the rectangular in cross-section structure 1d of the frame 1, which is integral with the channel 1a, and the opposite edge 4b of the molding channel 4 is nearer the enclosed side 4c of the molding channel 4, so that the edge 4a may be placed initially in overlapping relationship with the edge 2c of the screen 2, before the edge 4b of the channel 4 engages the normally enclosed side of the channel portion 1a of the frame 1. Thus, interference with and distortion of the screen 2 is substantially eliminated when assembling the molding channels 4, 5, 6 and 7 on the frame 1 and screen 2.

It will be noted that the screen locking members 3 may be made of plastic, metal, or other similar soft material, and that the screws 8, which are self-threading screws, extend through the molding channels 4, 5, 6 and 7 and into the outer leg of the channel portions 1a of the frame 1. At two opposite sides of the frame 1, these screws 8 extend into the screen locking members 3, and these screen locking members 3, being circular in cross-section, are pressed into the channel portions 1a of the frame 1 past the edge 1c at the center of said screen locking members 3, so that they are effectively locked frictionally in the channels 1a.

The operation of my window louver screen and frame is substantially as follows: When installing the screen 2, the screen locking members 3 are forced downwardly into the channel 1a, causing frictional engagement of the screen 2 with the screen locking members 3 concurrently to the downward movement of the screen locking members 3 in the channels 1a of the frame 1. This locking action causes stretching of the screen 2 and creates tension, which is applied to the rectangular in cross-section frame portions 1d, which renders the channel portion 1a free to frictionally hold the screen 2 and screen locking members 3 in secure position without undue stress on the actual resilient portion of the channel 1a, which engages the normally outer side of the screen locking members 3.

It will be noted that the rows 2b of the louvers of the screen 2 may be equally spaced relatively to the edges 4a and 5a of the molding channels 4 and 5, and that the overlapping edges 4a and 5a of the molding channels 4 and 5 provide for neat arrangement of the louvers of the screen 2 without deformation thereof.

Though I have shown and described a particular construction, combination and arrangement of parts and portions, I do not wish to be limited to this particular construction, combination and arrangement, but desire to include in the scope of my invention the construction,

combination and arrangement substantially as set forth in the appended claims.

Having thus described my invention, what I claim as new and desire to secure by Letters Patent is:

1. In a window screen frame, a rectangular frame having opposed sides provided with a cross-section comprising an open channel adjacent the rectangular marginal portions of said frame, a rectangular in cross-section structural means in connection with said channel portion and extending inwardly of said channel portion, away from said marginal portions, screen extending intermediate said opposite sides and having rows of parallel louver slats separated by tension means extending to the marginal limits of said screens, and locking means extending laterally of said tension means frictionally engaging said screen including said tension means at two opposite parallel edges and holding the same in said channel portions whereby said tension means is engaged and maintained in tension.
2. In a window screen frame, a rectangular frame having opposed sides provided with a cross-section comprising an open channel adjacent the rectangular marginal portions of said frame, a rectangular in cross-section structural means in connection with said channel portion and extending inwardly of said channel portion, away from said marginal portions, screen extending intermediate said opposite sides and having rows of parallel louver slats separated by tension means extending to the marginal limits of said screens, and locking means extending laterally of said tension means frictionally engaging said screen including said tension means at two opposite parallel edges and holding the same in said channel portions whereby said tension means is engaged and maintained in tension by said locking means, the remaining parallel edges of said screen extending in overlapped relationship with said frame, and molding channels having parallel legs extending around the edges of said frame and overlapping said screen.
3. In a window screen frame, a rectangular frame having opposed sides provided with a cross-section comprising an open channel adjacent the rectangular marginal portions of said frame, a rectangular in cross-section structural means in connection with said channel portion and extending inwardly of said channel portion, away from said marginal portions, screen extending intermediate said opposite sides and having rows of parallel louver slats separated by tension means extending to the marginal limits of said screens, and locking means extending laterally of said tension means frictionally engaging said screen including said tension means at two opposite parallel edges and holding the same in said channel portions whereby said tension means is engaged and maintained in tension by said locking means, the remaining parallel edges of said screen extending in overlapped relationship with said frame, and molding channels having parallel legs extending around the edges of said frame and overlapping said screen, the legs of said molding channels overlapping said screen being substantially longer than the legs thereof disposed on the opposite sides of said frame.
4. In a window screen frame, a rectangular frame having opposed sides provided with a cross-section comprising an open channel adjacent the rectangular marginal portions of said frame, a rectangular in cross-section structural means in connection with said channel portion and extending inwardly of said channel portion, away from said marginal portions, screen extending intermediate said opposite sides and having rows of parallel louver slats separated by tension means extending to the marginal limits of said screens, and locking means extending laterally of said tension means frictionally engaging said screen including said tension means at two opposite parallel edges and holding the same in said channel portions whereby said tension means is engaged and maintained in tension by said locking means, the remaining parallel edges of said screen extending in overlapped relationship with said frame, and molding channels having parallel legs extending around the edges of said frame and overlapping said screen,

the legs of said molding channels overlapping said screen being substantially longer than the legs thereof disposed on the opposite sides of said frame, said molding channels mitered at the corners of said frame.

4. In a window screen frame, a rectangular frame having opposed sides provided with a cross-section comprising an open channel adjacent the rectangular marginal portions of said frame, a rectangular in cross-section structural means in connection with said channel portion and extending inwardly of said channel portion, away from said marginal portions, screen extending intermediate said opposite sides and having rows of parallel louver slats separated by tension means extending to the marginal limits of said screens, and locking means extending laterally of said tension means frictionally engaging said screen including said tension means at two opposite parallel edges and holding the same in said channel portions whereby said tension means is engaged and maintained in tension by said locking means, the remaining parallel edges of said screen extending in overlapped relationship with said frame, and molding channels
